UNITED STATES PATENT OFFICE

2,140,799

MULTIPLE LIGHT SENSITIVE TUBE

Andrew A. Kucher, Dayton, Ohio

Application March 28, 1935, Serial No. 13,391

2 Claims. (Cl. 250—166)

This invention relates to improvements in multiple light sensitive tubes and has for an object, the provision of a light sensitive tube having a plurality of cathodes associated with a common anode and adapted to act in the same manner as a plurality of single light sensitive tubes. A further object of the invention is the provision of a light sensitive tube having a plurality of cathodes in close order or relationship, and a single anode common to all of said cathodes thereby making it possible to excite all of said cathodes with a single rectangular beam of light and to interrupt the light passing to one or more cathodes by means of recordings on a record passed between the light source and the cathodes.

Other objects of the invention will become apparent to those skilled in the art upon a perusal of the specification and the appended claims.

This application is a continuation in part of application Serial Number 436,264, filed March 17, 1930, now Patent No. 1,998,461 issued April 23, 1935, for Method and apparatus for recording and reproducing sound.

Referring to the drawings:

Figure 1 is a diagrammatic sketch showing the arrangement of the exciting lamp relative to the multiple tube with the record strip therebetween.

Figure 2 is a diagram in perspective showing the use of a multiple tube, the plurality of cathodes of which are each individually controlled by a record. This figure is similar to Figure 11 in the parent application above referred to except that circuits are shown associated with the tube, interrupters, an amplifier and a loud speaker.

Figure 3 shows a modification of the arrangement of the tube, the exciting lamp and the record.

Figure 4 shows another modified form of a multiple cathode light sensitive tube.

In reproducing recordings, a typical example of which is sound tracks, where a plurality of tracks are recorded in rows close together, applicant has devised an exciting lamp for passing a rectangular beam of light through a plurality of separate and individual recordings in a record simultaneously. This beam of light falls upon a multiple light sensitive tube having a plurality of cathodes, one for each sound track, and a single anode common to all of the cathodes.

Such a tube is shown in Figure 4, including a plurality of cathodes, three of which are designated by the numerals 10, 11 and 12. These cathodes are suitably insulated from each other. An anode is common to all of the cathodes, designated by the numeral 13. A suitable case 14

includes all of the electrodes and it may be vacuumized, gas-filled or filled with liquid, depending upon the type of light sensitive tube desired.

Each of the cathodes are provided with an external terminal, the terminals of the cathodes 10, 11 and 12 are designated by the numerals 15, 16 and 17, respectively, and a terminal 18 is provided for the anode.

Referring to Figure 2, a multiple tube 20 is provided with cathodes 21, 22, 23 and 24, having terminals 25, 26, 27 and 28, respectively. An anode 29 is common to all of the cathodes and is provided with a terminal 30. An exciting lamp 31 is provided with a reflector 32. A condensing lens 33 is positioned adjacent to the exciting lamp 31 and projects the rays of light in the form of a rectangular beam. The rectangular beam is further defined by means of a slit 34 formed in the mask plate 35. The rectangular beam, after leaving the plate 35, passes through the record 19 and the recordings in the sound tracks 36 effect the light falling upon the cathode 21, the recordings in the sound track 37 effect the light falling upon the cathode 22, and so on. The anode 29 is connected via its terminal 30 and a wire 40 to an amplifier 41 thereby connecting all of the internal cells of the tube in common to the amplifier.

A plurality of interrupter arms 42, 43, 44 and 45 are connected in common to a wire 46 which is also connected to the amplifier 41. These interrupter arms are respectively provided with contact points 48, 49, 50 and 51.

A plurality of stationary contact members 52, 53, 54 and 55 cooperate respectively with the contact points 48, 49, 50 and 51. A cam 56 carried by a shaft 57 cooperates with the interrupter arm 42 and allows the contact point 48 to make and break contact with the contact member 52 in accordance with the number of high points in the cam. A cam 58 is associated with the interrupter arm 43; a cam 59 is associated with the interrupter arm 44 and a cam 60 is associated with the interrupter arm 45. The shaft 57 may be driven by suitable mechanism moving the film 45 or by any other means such as by motor 61 having a pulley 62 and driving the shaft 57 by a belt 63 and a pulley 64.

Referring to Figure 1, a method of moving the record 19 is shown wherein the record passes over a plurality of rollers 65, 66, 67, and 68.

Having the apparatus connected as shown in Figures 1 and 2, so that the record passes across or cuts the light beam, the closing of the contacts of any one of the interrupter arms, for example, 55

the arm 42, connects the cathode 21, with which it is associated, to the amplifier 41 and a tone will be reproduced by the loud speaker 70 in accordance with the interruptions of the light beam by the sounding track 36 in the record 19. Other tones will be reproduced from the other sound tracks when the other interrupters are closed. If all of the interrupter arms close simultaneously, a tone, which is a composite of all of the recordings, will be reproduced by the loud speaker 70.

It is obvious that instead of the use of the interrupters for controlling the circuits between the cathodes and the amplifier, hand operated keys may be used thereby enabling an operator to play a tune.

It is likewise obvious that although the record is shown as a photographic record, perforations or slits in paper or cardboard sheets or strips may constitute a record.

Figure 3 is a modification in which an exciting lamp is designated by the numeral 71. A condensing lens 72 is positioned adjacent to the exciting lamp and a plate 73 is provided with a rectangular slit 74. The record, in this case, is in the form of a disc 75, recordings thereon being designated by the numerals 76, 77 and 78. This record is provided with a hub 79 and may be secured to a suitable shaft 80 by means of a nut 81. A multiple light sensitive tube 82 is provided having a common anode, the terminal of which is designated by the numeral 83, and a plurality of cathode terminals, two of which are designated

by the numerals 84 and 85. The record 75 is normally positioned between the slit 74 and the tube 82.

The new and improved multiple light sensitive tube makes it possible to reproduce recordings which have been recorded close together, thereby making it possible to construct very compact apparatus for reproducing the recordings.

Although the arrangement and operation of a simple embodiment of the invention is herein shown and described, it is obvious that many changes may be made in the form and structure shown without departing from the spirit of the invention as defined in the appended claims.

What is claimed is:

1. A multiple light sensitive tube comprising an evacuated envelope having a wall portion divided into separate insulated cathode element sections, a separate connection for each cathode mounted in the wall portion adjacent thereto, and an anode element coextensive in length with said cathode sections and mounted in the envelope to one side of the cathode sections.

2. A multiple light sensitive tube having an evacuated envelope, a plurality of cathode element sections located adjacent to and conforming with one wall surface of the envelope, said cathode sections being insulated from each other and coextensive with the adjacent wall section supporting the same, and an anode bar element located in the envelope in spaced relation to all of the cathode wall sections.

ANDREW A. KUCHER.
